UNITED STATES PATENT OFFICE.

FRANK E. THOMPSON AND JOHN W. STEDMAN, OF ELKHART, INDIANA;
SAID STEDMAN ASSIGNOR TO SAID THOMPSON.

BENCH-PLATE.

SPECIFICATION forming part of Letters Patent No. 349,619, dated September 21, 1886.

Application filed July 9, 1886. Serial No. 207,625. (No model.)

To all whom it may concern:

Be it known that we, FRANK E. THOMPSON and JOHN W. STEDMAN, citizens of the United States, residing at Elkhart, in the county of Elkhart and State of Indiana, have invented certain new and useful Improvements in Revolving Bench-Plates; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to a device or revolving plate for holding tinners' or metal-workers' tools, stakes, shears, &c.; and it consists in the novel features more fully hereinafter set forth, claimed, and shown in the annexed drawings, in which—

Figure 1 is a plan view. Fig. 2 is a cross-section on the line $\alpha\alpha$ of Fig. 1. Fig. 3 is a side view of the several parts detached and arranged in their relative positions, and Fig. 4 is a side view of the revolving plate.

The ring A is designed to be let into an opening cut in the bench for its reception. The outer edge is beveled, and an annular flange, a, extending from its upper edge, is designed 30 to support the ring and keep it level, also to prevent its dropping through the opening in the bench. The circular plate B is fitted within the ring, and its edge is beveled to correspond with the interior of the ring to prevent 35 its dropping through and to keep it level, and to make a seat for it to revolve on. An annular flange, b, projecting from its upper edge and seated in a corresponding rabbet, a', in the ring, affords a further support. The truss-brace C holds the ring and plate in position. It is of a length greater than the diameter of 40 the lower outer edge of the ring, so it may get a purchase at each end on the bench on diametrically-opposite sides of the opening. A bolt, D, passed through the center of the plate B and truss, is threaded on its lower end and provided with the hand-nut d, for drawing the parts in place and firmly holding the ring and plate in position. The plate B is preferably 45 of a thickness equal to the thickness of the

ring, and is provided with a series of openings or sockets, a², for the reception of the several tools, stakes, &c. The truss-brace can be used to hold the plate on any thickness of bench.

Prior to our improvements the apertured or socketed plate was seated in a ring fitted in a circular recess cut in the bench and held therein by a bolt passed centrally therethrough and through an aperture in the bench in the bottom of the recess, the lower end of the bolt being threaded and provided with a hand lever or nut which is adapted to engage the lower side of the bench. Such construction is not broadly claimed, from which ours differs essentially in having an opening cut entirely through the bench and the plate-supporting ring fitted wholly therein. The plate and ring are held in place by the truss C, which is sleeved on the lower end of the bolt and has 55 its ends extended beyond the opening in the bench and engaged with the bench on diametrically opposite sides of the opening. By this construction it matters little whether the ring A is of a greater thickness than the bench 60 or not, as the parts will be securely and firmly held in place.

Having thus described our invention, what we claim, and desire to secure by Letters Patent, is—

The combination, with the bench having an opening cut therethrough, and the ring A, having an offset or flange projecting from its outer edge and rabbeted on its inner edge fitted in said opening, of the apertured or socketed 80 circular plate B, seated in the ring and provided with a flange resting in the rabbet, the bolt D, threaded at its lower end, the truss C, mounted on the bolt and having its ends extended and engaging the bench on diametrically-opposite sides of the opening, as shown, and the hand-nut d, substantially as and for the purpose set forth.

In testimony whereof we affix our signatures in presence of two witnesses.

FRANK E. THOMPSON.
JOHN W. STEDMAN.
